UNITED STATES PATENT OFFICE

EARL DWIGHT COVELL, OF PHILADELPHIA, PENNSYLVANIA, ASSIGNOR TO THE COVELL CORPORATION, OF WILMINGTON, DELAWARE, A CORPORATION OF DELAWARE

ART OF WALL CONSTRUCTION AND BUILDING UNIT THEREFOR

Application filed August 15, 1929. Serial No. 386,045.

This invention relates to the art of wall construction and building units therefor. More particularly, the instant improvements have reference to building units of the type embodying a depression in one or both of the horizontal faces, said depression or depressions being defined in part by a ridge or ridges extending along, or more or less closely adjacent to, one or more of the vertical faces, with appropriately situated spacing lugs; whereby, when such blocks are laid horizontally, intervals opening to one face only are formed for the direct introduction of bonding material. Sometimes it is more convenient to use any readily available standard building units and to form the intervals for introduction of bonding material by using separate or unattached spacer lugs and barrier ridges; while in other instances separate or unattached spacer lugs and barrier ridges may be used with greater convenience.

The fundamental of the present invention is a novel art of wall construction comprising laying up building units, appropriately spaced apart by attached or separate spacing lugs and barrier ridges, to furnish intervals opening directly to one face enabling completion by the introduction of bonding material by mechanical or other means. In some instances, however, as in the case of back-up units, it may be found convenient to dispense with the barrier ridge or ridges.

Another feature has reference to the location of the attached or separate barrier ridges and spacing lugs so that the several units may be varied according to the type of construction being executed.

Other features of advantage and objects attained will be apparent from the following disclosure, while it is to be understood that in the reduction to practice of my invention, numerous modifications, or other combinations and arrangements, or location of the spacing lugs and barrier ridges, may be resorted to without departure from the scope of my present improvements.

In the drawings:—

Fig. I is a perspective view illustrating a portion of a wall constructed from building

units in accordance with the present invention.

Figs. II and III are perspective views of building units embodying face and end barrier ridges as well as spacer lugs. 55

Fig. IV is a perspective view of a unit having end barrier ridges only.

Fig. V is a sectional view, taken as indicated by the arrows V—V in Fig. 1.

Figs. VI and VII are perspective views 60 showing other illustrative types of building units embodying barrier ridges and spacer lugs capable of being employed in accordance with my invention.

Fig. VIII is a similar view of a hollow 65 body type of unit.

Fig. IX shows a form of unit with spacer ridges at intervals away from the ends of said unit; and

Fig. X is a similar view but illustrating 70 the adaptation of spacer lugs only.

The several units herein illustrated are all of such configuration that they may be fabricated by molding, tamping, die pressing or other means from clay, concrete, cement-cinder or other composition. Furthermore, all corresponding parts are similarly designated by like references, with only those differing in location or purpose distinctively characterized to avoid overlapping descriptive matter. 75 80

Referring firstly to the various forms of building units illustrated, that designated 1 in Fig. II has a depression 2 in its horizontal face defined by a ridge 3 which is co-extensive 85 with one lateral face and spacing lugs 4 on or near the opposite face and special relation to the unit horizontal ends. This unit 1, furthermore, has an end ridge or lug 5 which is continuous with and of the same height 90 as one lateral face; while the purpose thereof will be later explained.

In the modified unit 6 of Fig. III, the depression 2 in its face is in part bounded by a continuous ridge 7 along one lateral face 95 and horizontal end of the unit; an end ridge or lug 5 as before described; and but one spacing lug 8 remote from the ridge 7 aforesaid. The purpose of this modified unit is to enable the construction of corners. 100

Unit 9 of Fig. IV is a form of "backup" block with depression 2 in a horizontal face bounded at the ends by ridges 10 which provide the spacing for the horizontal joints. 5 This also enables the joint material at the ends of the unit to be projected through to a temporary or permanent barrier wall at one side of the "backup". Unit 11 of Fig. VI is a modified form of the unit 1 of Fig. II in 10 which the end lug 5 is omitted. I use this unit 11 also as a "backup" block, the purpose being to enable the joint material at the ends of the unit to be bonded onto a temporary or permanent barrier wall. The unit 12 of Fig. 15 VII is another modified form of the unit 1 of Fig. II in that but one lug 13 is provided to secure the horizontal joint spacing. Unit 14 of Fig. VIII is a slight modification of the unit 11 of Fig. VI. This type 20 of unit 14, it will be seen, is of the hollow tile variety, being provided with spaced apertures 15 therethrough, while the depression 2 is defined by a longitudinal ridge 3, and corner spacing lugs 16. 25 Unit 17 of Fig. IX has a depression 2 in one face with paralleling ridges 18 which preserve the spacing of the horizontal joint for the subsequent introduction of bonding material *m* by mechanical or other means. 30 Unit 19 of Fig. X embodies upstanding lugs 20 that enable the spacing of the horizontal joints for the subsequent introduction of bonding material *m* by mechanical or other means. 35 Units 9, 11, 14, 17 and 19, may be used where there is a barrier at one side of the "backup" wall face, obviating the necessity of retaining all the bonding material *m* in the horizontal and vertical joints of the unit 40 faces when introduced from a side of the wall. In building a wall as depicted in Figs. I and V, I employ in the outer thickness 21, units 45 of the type 1—Fig. II—laid end to end; while at the corners use in made of the units 6, shown in Fig. III, since said units have one 50 face adapted for the corner return. The inner wall thickness 22 may be constructed in spacial relation to the wall 21 to provide an interval *i* and entirely of units 9, 11, 14, 17 and 19; as shown, respectively, in Figs. IV, 55 VI, VIII, IX and X. However, the inner wall is depicted as being constructed wholly of units 9, as shown in Fig. IV. These units 9, for example, are laid with the horizontal 60 joint spacings 23 open directly to the rear or inner face of the wall, care being taken to separate them one from another longitudinally to allow sufficient vertical opening 24 for the introduction of the bonding material *m* therebetween; as later on more fully explained.

In laying the two thicknesses of walls 21 and 22, I prefer to erect 21 first; following the laying of the units 1 and 6, I introduce 65 bonding material *m* into the open horizontal

joints afforded by the depressions 2 and vertical joints 25 from the in side of said wall. I then prefer to coat a face of the wall 21—the in face for example—with plaster or waterproof material by mechanical or other means before laying the "backup" wall 22. This wall 22 is then laid as hereinbefore described and the horizontal and vertical joints 23, 24, as well as the vertical interval *i* when provided, are filled with a suitable bonding material *m* from the in face. 75

It will be noted that in introducing the bonding material *m* by compressed air or other suitable means, I provide a bond of the joint material onto one side of the wall 22; 80 which unites the wall into a monolithic mass.

From the foregoing, it will be seen that by proper choice and arrangement as between the units 1, 6, 9, 11, 12, 14, 17 and 19, I am able to set up an angular wall structure with 85 a flush outer face and a system of internal channeling which is directly accessible from one side so that the bonding material *m* may be directly introduced into the open joints 2, 25; or 23, 24; subsequent to laying of the 90 wall or a section thereof.

It is readily evident to those skilled in the art that the introduction of mortar, for instance by a cement gun or similar device will result in speed of construction as well as provide a wall of great strength and rigidity. Upon filling of the interstices 2, 25; or 23, 24; by such a method and setting of the cement or other suitable bonding material *m*, it will be apparent that the component units 100 21, 22, are securely bonded together to form a solid structure or wall. If walls of greater thickness than shown in Fig. I are desired, they may, obviously, be had by adding one or more inner sections 22, constructed from any 105 of the "backup" units hereinbefore described.

Still other variations such for example as rights and lefts of certain of the types of units described, and the moving of the spacing lugs and barrier ridges from the illustrative position shown in the different figures, are obviously possible within the scope of my invention.

Having thus described my invention, I 115 claim:

1. A wall construction comprising building units laid with predetermined spacings to provide horizontal and vertical joints, each said unit embodying a barrier ridge on or closely adjacent to a vertical face thereof and a barrier ridge outstanding from certain of the transverse vertical faces with a spacing lug or lugs on a horizontal face in spacial relation to the ends thereof, said ridges and lugs thereby affording predetermined open horizontal and vertical intervals directly accessible from one face of the wall only for the subsequent introduction and reception of bonding material. 125 130 135

2. A wall construction comprising units laid with appropriate spacing to provide vertical joints and predeterminedly spaced horizontal joints, each said unit embodying a barrier ridge on or closely adjacent to a vertical face with a lug or lugs on a horizontal face in spacial relation to the unit ends, said ridge and lug or lugs affording open intervals directly accessible from one face of the wall only for the subsequent introduction and reception of bonding material.

3. A lining wall construction comprising units laid with appropriate spacing apart longitudinally to provide vertical joints and predeterminedly spaced horizontal joints, each said unit embodying spacing lugs on a horizontal face or faces in spacial relation to the ends thereof that afford open intervals directly accessible from one face of the wall for the subsequent introduction and reception of bonding material.

4. A wall construction involving introduction of appropriate bonding material by mechanical or other means from one side of a backup wall composed of units embodying lugs on a horizontal face or faces in spaced relation to the ends thereof to bond the same onto one surface of a facial wall by forced passage through vertical and interrupted horizontal spaces between the units of the backup wall, said facial wall comprising units with barrier ridges and spacing lugs setting apart horizontal and vertical intervals accessible from the inner face only, and the introduced material bonding said units together and concurrently uniting the two walls aforesaid into one common mass.

5. A wall comprising units predetermining a flush face, each said unit embodying a barrier ridge along vertical faces thereof with spacing projections upon a horizontal face in spacial relation to the ends thereof, whereby predetermined horizontal and vertical intervals are formed that extend into close proximity to one wall face, said intervals being open to the other wall face only for direct accessibility in subsequently introducing a bonding agent.

6. A backup wall constructed from units laid an appropriate distance apart longitudinally to form vertical channels, each said unit including spacers which predetermine interrupted horizontal intervals, said vertical channels and horizontal intervals being open at the rear face of the wall for direct accessibility in subsequently introducing a bonding agent, a facial wall, and said bonding agent in certain of the channels and intervals extending to the surface of the facial wall and being bonded upon it to form headers to unite the backup wall to said facial wall.

7. A lining wall constructed from units laid an appropriate distance apart longitudinally to form vertical channels, each said

unit having barrier ridges along paralleling vertical faces thereof which predetermine interrupted horizontal intervals, said vertical channels and horizontal intervals being open to the exposed face of said wall for direct accessibility in subsequently introducing appropriate bonding material.

8. As a new article of manufacture, a building unit with a depression in one of its horizontal faces defined in part by a ridge extending along a vertical face, and by opposing projections on said horizontal face away from the angular corners thereof.

9. As a new article of manufacture, a building unit with a depression in a horizontal face defined in part by a ridge extending along the vertical sides adapted to be exposed at the face of a wall, and by a projection in said horizontal face away from the angular corners thereof.

10. As a new article of manufacture, a building unit with a depression in a horizontal face defined in part by a ridge extending along one vertical face and by opposing projections on said horizontal face spaced relative to the corners thereof and aligned with the opposed vertical face, and a spacing ridge extending outward from another of the vertical faces.

In testimony whereof, I have hereunto signed my name at Rockmart, Georgia, this 9th day of August, 1929.

EARL DWIGHT COVELL.
